Specification for Design.

Patented May 11, 1920.

Application filed November 1, 1919. Serial No. 335,189. Term of patent 7 years.

To all whom it may concern:

Be it known that I, HARRY T. ABOLIN, a citizen of the United States of America, residing at Woodridge, in the county of Bergen and State of New Jersey, have invented a new, original, and ornamental Design for an Article of Manufacture, of which the following is a specification, reference being had to the accompanying drawing, forming part thereof.

The figure is a plan view of a portion of a printed fabric showing an embodiment of my new design. It is to be understood how-

ever that my new design may be applied not only to fabrics, but also to wall paper, wrapping paper, or similar articles having surface ornamentation, without departing from what I claim as my invention.

I claim:—

The ornamental design for an article of manufacture, substantially as shown and described.

HARRY T. ABOLIN.
